UNITED STATES PATENT OFFICE.

ALLEN COOKE, OF DANVILLE, ILLINOIS.

STEAM BELL-RINGER.

SPECIFICATION forming part of Letters Patent No. 296,139, dated April 1, 1884.

Application filed January 9, 1884. (No model.)

To all whom it may concern:

Be it known that I, ALLEN COOKE, a citizen of the United States, residing at Danville, in the county of Vermilion and State of Illinois, have invented certain new and useful Improvements in Steam Bell-Ringers, of which the following is a specification, reference being had therein to the accompanying drawings.

10 This invention relates to improvements in steam bell-ringers, and has for its object to provide locomotives with a simple and efficient means of ringing the bell. This object is attained by the mechanism illustrated in the 15 accompanying drawings, forming a part of this specification, in which—

Figure 1 is an elevation showing the engine in connection with a bell. Fig. 2 is a sectional view. Fig. 3 is an end view. Fig. 4 is 20 a detached view of the valve-chest, and shows its internal construction. Figs. 5, 6, 7 are detailed views of the valve D and plate E. Fig. 8 is a detailed view of the pitman and bell-crank connections.

25 The letter A indicates the cylinder of the engine.

B is the valve-chest.

C is the piston.

D is the valve.

30 E is a circular plate having opening E' E'', by means of which the valve-stem is introduced and held in its place and permitted to slide freely in the hollow of piston C and piston-rod I, as shown in Fig. 2. The plate E is 35 fitted in a recess in the piston C, and is secured thereto by the screws e.

F is an enlarged portion of the valve-stem, and is fitted to slide back and forth in a central opening in the bottom of the cylinder B. 40 The upper end of the valve-stem F' is enlarged, and is fitted to the hollow I' of piston and piston-rod. The reduced part F'' is fitted to the semicircular part of the opening E' in plate E, and the reduced part F''' is fitted 45 to the opening D' of the valve D, and the enlarged part F'' enters a semicircular recess therein. G is the head of the cylinder, and is provided with the usual stuffing-box.

H is a short cylinder fitted into the valve-

chest B, and is provided with a stud, H', 50 which is fitted into the opening D' of the valve D, and serves to keep it in its proper position.

I is the piston-rod, and is provided with a bifurcated head, K, to which is pivoted a pitman, L, of square section, which fits into a hollow connecting-rod, L', by means of which motion is imparted to the bell-crank, and is constructed in this manner in order that it may give or slide as much as the bell may require when ringing.

M is the induction-passage for the steam or compressed air, and M' is the exhaust.

N is the independent air-passage communicating with the top of the cylinder above the 65 piston, and communicating with the exhaust M'.

N' is the induction-passage communicating with the inside of the valve-chest and through the bottom of the cylinder A to the interior 70 thereof. The cylinder A is cast with its bottom head solid, with an aperture in the center for the valve-stem to pass through, and faced to receive the chest for slide-valve for working the piston, and is also provided with an independent escape for the air or steam above the piston-head, in order that the piston may not be checked or retarded in its upper stroke. This independent escape or outlet is by preference connected to the exhaust-outlet, that 80 all discharges may be in one.

The steam or air is admitted to the chest beneath the cylinder and then into the cylinder, which pushes the piston up. This starts the bell to ring. As the piston is thrown full up and 85 the slide-valve is connected to the piston, it is drawn up, covering the inlet-port and opening the outlet-port for the steam or compressed air to escape as the piston is driven back by the return swing of the bell. This swinging full back 90 opens the inlet-port from the chest, and the piston is worked continuously by the steam at half-stroke, and the return swing of the bell may be stopped at will, without turning off the steam, simply by the bell-cord preventing the 95 return swing of the bell to drive the piston full down, and may be started again by simply starting to ring the bell by the cord.

Having described my invention, what I desire to secure by Letters Patent, and claim, is—

1. In a steam bell-ringer, the combination 5 of a cylinder with one head cast solid, having central aperture for valve-stem, of valve-chest secured thereto, of slide - valve therein, of valve-stem, of hollow piston and plate secured thereto, as described, and for the purposes set forth.
2. In a steam bell-ringer, a cylinder having

one head cast solid, in combination with a valve and a valve-chest having a cylindrical lining provided with a stud, for the purposes described and set forth.

In testimony whereof I affix my signature in presence of two witnesses.

ALLEN COOKE.

Witnesses:

P. WILBER,
W. M. BANDY.
